UNITED STATES PATENT OFFICE.

JOHN BELL SHELTON, OF SAN FRANCISCO, CALIFORNIA.

ADJUSTABLE DECK-SUPPORT FOR CARS.

1,349,735.

Specification of Letters Patent. Patented Aug. 17, 1920.

Application filed October 8, 1919. Serial No. 329,219.

To all whom it may concern:

- Be it known that I, JOHN BELL SHELTON, a citizen of the United States, residing at San Francisco, county of San Francisco, State of California, have invented a certain new and useful Improvement in Adjustable Deck-Supports for Cars, and declare the following to be a full, clear, and exact description of the same, such as will enable others skilled in the art to which it pertains to make and use the same, reference being had to the accompanying drawings, which form a part of this specification.
- 15 My invention relates to an adjustable deck support for a combined freight or stock car shown in the accompanying drawings and more particularly described in the following specification and claims.
- 20 One of the objects of this invention is to provide a deck support for an adjustable double deck freight or stock car which is secured to the upright members of the frame of the car and is adapted to swing between slats of the car regularly secured to said upright members. Much time and labor is thus saved in fitting up a car with devices for supporting an adjustable deck in an elevated position.
- 25 Another feature of the invention consists in so constructing the casting which supports the swinging arm or bracket that it may be used on either side of the car—in other words there are "no rights or lefts" as usual in adjustable deck supporting devices now in common use, thus the time and labor of sorting out the "rights" from the "lefts" is saved when fitting up a car.
- 30 A further advantage of the present invention over devices previously employed is due to a great reduction in the weight of the several parts employed without sacrificing the strength of the supporting device.
- 35 With the foregoing and other objects in view which will appear as the description proceeds, the invention consists in the combination and arrangement of parts and in the details of construction hereinafter described and claimed, it being understood that changes may be made in the precise embodiment of the invention herein disclosed without departing from the spirit of the same.

In the drawings accompanying this specification:—

55 Figure 1 is a horizontal sectional and plan view of the car showing a plurality of the deck supporting devices secured to the upright members of the car frame, the supporting devices being connected together in groups for simultaneous operation.

60 Fig. 2 is a vertical cross-sectional view through a car showing the device in position to support its adjustable deck.

65 Fig. 3 is a fragmentary plan view of an adjustable deck car with the roof removed—showing means for raising the adjustable deck and in dotted lines the deck supporting devices as they would appear when sustaining the latter.

70 Fig. 4 is an enlarged detail sectional view, showing the device secured to a fragment of one of the upright posts of the car frame and in position to sustain the adjustable deck—a fragment of which is shown.

75 Fig. 5 is a perspective view of the L-shaped casting secured to one of the uprights of the car frame and in which the swinging arm or bracket is pivoted.

80 Fig. 6 is a cross-sectional view through the device as when attached to an upright post of the car frame taken on line 6—6 of Fig. 4.

85 Referring now to the letters of reference placed upon the drawings:—

A, denotes a freight car. B, a right and left screw-threaded shaft extending longitudinally within the car and supported by suitable hangers secured to the roof timbers. C, is a ratchet lever for actuating the shaft.

90 D, D', are traveling beams carried respectively by the right and left screw-threaded portions of the shaft. E E are hoisting cables secured to the ends of the respective beams D, D' and supported by sheaves F bolted to the side walls of the car. G denotes an adjustable deck to which the cables are connected.

95 The deck G includes a rectangular frame H bolted to channel irons H' forming its side sills. I, denotes the floor secured to the deck.

100 The foregoing is briefly descriptive of cars of this class—the several parts forming no part of the invention, being only re-

ferred to here that the operation of the present invention may be readily understood.

J, denotes an L-shaped casting adapted to be bolted to the upright members K of the car frame between the usual spaced slats L nailed to said upright members. J', indicates a pair of projecting ears, spaced apart and formed integral with the L-shaped casting. M, indicates a swinging arm pivoted between the ears J' of the casting J by a vertical pin N, secured by a cotter N'.

The free or outer end of the swinging arms are rounded to form an upstanding dowel pin M' adapted to enter holes provided to receive them in frame H of the adjustable deck.

Hooked bolts Q carried by rails R loosely embrace the vertical pins M'—that the several arms may be operated as a unit,—the preferred arrangement being to group together the several supporting arms on each side of the entrance doors S, as clearly indicated in Fig. 1 of the drawings.

T, is a removable pin supported by a chain U, secured to the car frame which is adapted to enter an aperture t in the projecting ears J' of the L-shaped casting for securing the swinging arm in its "closed" or "open" position as may be required.

Having indicated the several parts by reference letters, it will be apparent that the adjustable deck when raised by means of its operating mechanism, may be supported in its elevated position by swinging the supporting arms beneath the frame of the deck which is then lowered so that the dowel pins on the swinging arms may enter the holes provided in the frame of the deck for their reception.

If desired the dowel pin on the end of the arms may be dispensed with.

The removable T is now inserted in the hole t in the L-shaped casting to secure the swinging arms in their "open" position for supporting the adjustable deck.

When it is desired to lower the deck the pins T are first removed, the deck is then raised sufficiently to permit the swinging arms to be shifted out of the path of the adjustable deck which is then lowered to the floor of the car—the pins T being inserted as before but on the opposite side of the swinging arms to secure the latter in their "closed" position.

Having thus described my invention, what I claim is:

1. In a car of the character described, an adjustable platform, means for raising and lowering said platform, means for supporting said platform when raised, comprising a plurality of castings adapted to be secured to spaced upright members of the car frame, a horizontally swinging bracket arm pivoted to each of said castings adapted to

swing beneath the platform to support the latter, and also between the upright members of the car frame and out of the path of the platform, that the latter may be lowered to the floor of the car, and slats connected with the free ends of a plurality of said swinging bracket arms, whereby they may be operated simultaneously.

2. In a car of the character described, an adjustable platform, means for raising and lowering said platform, means for supporting said platform when raised comprising a plurality of castings adapted to be bolted to spaced upright members of the car frame, a horizontally swinging bracket arm pivoted to each of said castings adapted to swing beneath the platform to support the latter and also to swing between the upright members of the car frame out of the path of the adjustable platform, and a fastening device arranged to secure said swinging arms in their "open" or "closed" positions.

3. In a car of the character described, an adjustable platform, means for raising and lowering said platform, means for supporting said platform when raised comprising a plurality of castings adapted to be bolted to spaced upright members of the car frame, a relatively short horizontally swinging bracket arm pivoted to each of the castings adapted to swing under the platform to support the latter and also to swing between the upright members of the car frame out of the path of said platform whereby the platform may be lowered, and a removable vertical pin adapted to enter an aperture in said castings and arranged to secure the swinging bracket arms in their "open" or "closed" positions.

4. In a car of the character described, an adjustable platform, means for raising and lowering said platform, means for supporting said platform when raised comprising a plurality of L-shaped castings adapted to be bolted to the upright members of the car frame, a horizontally swinging arm pivoted between ears integral with the L-shaped castings, rails connecting a plurality of said arms together for simultaneous operation, and removable vertical pins adapted to enter holes provided in the ears of said castings and arranged to secure the swinging brackets in their "open" or "closed" positions.

5. In a car of the character described, an adjustable platform, means for raising and lowering said platform, means for supporting said platform when raised, comprising a plurality of castings adapted to be bolted to the upright members of the car frame, a swinging arm pivoted to each of said castings having at its free end an upstanding vertical dowel pin adapted to enter dowel holes provided in the frame of said adjustable platform, means for securing the swinging arms in either an "open" or "closed" position

with reference to the adjustable platform, and a rail loosely connected with the dowel pins of the free ends of said swinging arms, whereby they may be operated as a unit.

- 5 6. In a car of the character described, an adjustable platform, means for raising and lowering said platform, means for supporting said platform when raised, comprising a plurality of castings adapted to be bolted to
10 the upright members of the car frame, a horizontally swinging arm pivoted to each of said castings having at its free end an upstanding dowel pin adapted to enter dowel holes provided in the frame of said adjustable platform, means for securing the swing-

ing arms in either an "open" or "closed" position with reference to the adjustable platform, a rail, and a plurality of hook-shaped bolts secured to said rail and pivotally engaging the dowel pins of the free 20 ends of the respective swinging arms, whereby the latter may be "opened" or "closed" as a unit.

In testimony whereof I sign this specification in the presence of two witnesses.

JOHN BELL SHELTON.
